(57) **CLAIM**

The ornamental design for an actuator box with a controlling key, as shown and described.

DESCRIPTION

FIG. 1 is a perspective view of an actuator box with a controlling key showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view wherein the broken lines define portions of the actuator box that form no part of the claimed design.
